(57) **CLAIM**

The ornamental design for a sphygmomanometer with wireless communication device, as shown and described.

DESCRIPTION

FIG. 1 is a front, top, and right side perspective view of a sphygmomanometer with wireless communication device showing our new design;

FIG. 2 is a rear, bottom, and left side perspective view thereof;

FIG. 3 is a right side view thereof;

FIG. 4 is a left side view thereof;

FIG. 5 is a reduced front, top, and right side perspective view showing a condition in which a wrist band is unfastened thereof;

FIG. 6 is a reduced rear, bottom, and left side perspective view showing a condition in which the wrist band is unfastened thereof;

FIG. 7 is a reduced rear view showing a condition in which the wrist band is unfastened thereof;

FIG. 8 is a top view showing a condition in which the wrist band is unfastened thereof;

FIG. 9 is a bottom view showing a condition in which the wrist band is unfastened thereof;

FIG. 10 is a reduced right side view showing a condition in which the wrist band is unfastened thereof;

FIG. 11 is a reduced left side view showing a condition in which the wrist band is unfastened thereof;

FIG. 12 is an enlarged partial view in the area of arrow lines 12-12 in FIG. 5;

FIG. 13 is an enlarged partial view in the area of arrow lines 13-13 in FIG. 6;

FIG. 14 is an enlarged partial view in the area of arrow lines 14-14 in FIG. 7;

FIG. 15 is an enlarged partial view in the area of arrow lines 15-15 in FIG. 10;

FIG. 16 is an enlarged partial view in the area of arrow lines 16-16 in FIG. 11; and,

FIG. 17 is an enlarged partial view of a joint portion between a body and a cuff thereof.

The dashed broken lines shown in the figures illustrate portions of the sphygmomanometer with wireless communication device that form no part of the claimed design.
